BICYCLE

Eugene D. Tilley, Fisher, Ark.

Application January 2, 1951, Serial No. 13,641

Term of patent 14 years

(Cl. D90—8)

To all whom it may concern:

Be it known that I, Eugene D. Tilley, a citizen of the United States of America, residing at Fisher, in the county of Poinsett and State of Arkansas, has invented a new, original, and ornamental Design for a Bicycle, of which the following is a specification, reference being had to the accompanying drawing, forming part thereof.

Figure 1 is a left side elevational view of a bicycle showing my new design.

Fig. 2 is a top plan view of same.

Fig. 3 is a front elevational view of same.

Fig. 4 is a right side elevational view of same.

The dominant features of my design reside in those portions shown by means of full lines in the drawing.

I claim:

The ornamental design for a bicycle, substantially as shown and described.

EUGENE D. TILLEY.
